UNITED STATES PATENT OFFICE.

JAMES G. SMITH, OF COVINGTON, KENTUCKY, ASSIGNOR OF ONE-THIRD
TO GEORGE HILDENBRANDT, OF COVINGTON, KENTUCKY, AND ONE-
THIRD TO GEORGE W. DAVY, OF CINCINNATI, OHIO.

LUBRICATING DEVICE FOR JOURNAL-BOXES.

No. 828,066.

Specification of Letters Patent.

Patented Aug. 7, 1906.

Application filed October 7, 1904. Serial No. 227,544.

To all whom it may concern:

Be it known that I, JAMES G. SMITH, a citizen of the United States, residing at Covington, in the county of Kenton and State of Kentucky, have invented certain new and useful Improvements in Lubricating Devices for Journal-Boxes, of which the following is a specification.

My invention relates to an automatic lubricator for journal-boxes.

This invention particularly relates to an improvement over the device shown in my former patent, No. 634,860, granted October 10, 1899.

The features of my invention are more fully set forth in the description of the accompanying drawings, forming a part of this specification, in which—

Figure 1 is a central vertical section. Fig. 2 is a top plan view. Fig. 3 is a perspective view of the tray. Fig. 4 is a central vertical section through the supporting-legs.

1 represents the cellar of a journal-box of a locomotive, for instance. This cellar may be 25 of any shape. I form a waste-bearing tray 2 shaped to fit the cellar, said tray being provided with semicircular ends 3, which are lined with the wearing-strips 4. The tray is preferably of brass or sheet metal and the 30 wearing-strips of wood or similar material to prevent the semicircular ends from grooving the axle.

5 represents the car-axle, and 6 the car-brass.

7 represents a section of the support for the journal-box.

In my first-named patent the tray is provided with elliptic springs G, designed to form self-adjusting supports for the tray. I have 40 found that these springs continually break and bend from shape and are unsuitable. Therefore I have sought to provide an oil-tray with self-contained spring-legs, as many as desired, and adapted to stand on the floor 45 of the cellar and support the tray and in which the coil-springs are not exposed either in the tray or in the cellar, the spring-legs being projected from the bottom of the tray, so that the tray can be simply placed in the cellar and automatically compressed into position. The tray of course is filled with packing (not shown) which is saturated with oil and which engages the axle.

The spring-legs consist of two telescoping tubes, the outer one 8 being open downwardly. This tube is inserted through the bottom of the tray and soldered thereto. Into the open end of the tube 8 is inserted an upwardly-opening tube 9, and within and between these tubes is placed a coil-spring 10. 55 To prevent the tube 9 from coming out of the tube 8, the tube 9 is provided with a flanged ring 11 at its upper end, and the tube 8 is provided with a flanged ring 12 at its lower end of less diameter than the ring 11. This form 60 of leg is entirely self-contained and automatic in its spring action. It is obvious that as the outer tube 8 is fixed to the bottom of the oil-tray this tube 8, projecting up into the bottom of the oil-tray, does not move 65 relative to the oil-tray, but that the oil-tray and this tube 8 move upwardly or downwardly as a unit upon the telescoping tube 9, the spring of course giving the proper compression. The telescoping member 9 has a 70 foot 16 adapted to stand on the floor of the cellar and support the tray therein. Although not essential to the practical operation of the device, I prefer to place in the bottom of the tray a spring-platform 13, having 75 four cups 14 in the respective four corners, into which fit the springs 15, seating upon the floor of the tray. The purpose of this is to stir up the packing in the tray independent of the adjustment of the packing vertically 80 with the tray. This tubular form of leg permits the under telescopic member to be telescoped substantially its entire length within the upper telescopic member, which permits the floor of the waste-bearing tray to lie near 85 the floor of the cellar initially, thus utilizing practically the entire depth of the cellar as a waste-contained space.

It will be noted that in the preferred form two or more independent spring-controlled 90 telescoping legs are shown. This gives an independent yielding action at each of the points of support, the advantage of which is obvious.

Having described my invention, I claim— 100
1. In a lubricating device for journal-boxes, an oil-cellar, a waste-bearing tray fitting said cellar, an inverted tube attached to the bottom of said tray, a telescoping member inserted in said inverted tube adapted to 105 stand on the floor of the cellar and support

the tray, a coil-spring between said telescoping members and means for maintaining said telescopic relation whereby the tray is provided with a self-contained, spring-controlled telescopic leg, substantially as described.

2. In a lubricating device for journal boxes, an oil-cellar, a waste-bearing tray fitting said cellar, an inverted tube attached to the bottom of said tray, a telescopic mantle inserted in said inverted tube adapted to stand on the floor of the cellar and support

the tray, a coil-spring between said telescopic members, means for maintaining said telescopic relation, and an independent platform 15 mounted on springs upon the tray, substantially as described.

In testimony whereof I have hereunto set my hand.

JAMES G. SMITH.
